AUTOMATIC STARTING SYSTEM

Marion W. Morris, Logansport, Ind., assignor, by
mesne assignments, to Eclipse Machine Com-
pany, Elmira Heights, N. Y., a corporation of
New York

Application June 29, 1935, Serial No. 29,924

8 Claims. (Cl. 290—38)

This invention relates to automatic starting systems for the internal combustion engines of motor vehicles and the like, and is directed more particularly to a starting system which is capable of initially starting the engine of such a vehicle, and automatically re-starting the engine if it stalls or stops.

It is well known in the art to provide starting systems in which the switch for the starting motor is automatically reclosed upon a false start or stalling of the engine, but in such systems with which I am familiar it has always been the practice to provide a somewhat arbitrary time delay, such as a vibrating reed, a dash pot or the like, or a holding coil which is released by dropping off of the generator current below a predetermined minimum. The main objection to such starting systems has been that this arbitrary time period, if not of sufficient duration, would under some conditions reclose the starter motor switch and actuate the starter motor either before the engine stopped spinning or rocking, or before the starter motor stopped spinning; in the case of a false start, for example, and consequently the full cranking force of the starting motor would not be imparted to the engine. On the other hand, if this time delay period were made too long, disadvantages arose from the fact that too long a period intervened between stalling or stopping of the motor and re-cranking thereof.

In addition, the prior art systems which are known to me possessed another disadvantage in that they employed a holding coil for opening and maintaining open the circuit through the starting motor switch relay, which coil was energized by the current produced by a generator driven by the vehicle engine. Consequently, operation of the system was dependent upon proper generator current, and development of less than a predetermined current rendered the system inoperative, whether caused by low battery voltage or improper generator operation.

The present invention has for its primary purpose the provision of an automatic starting system which eliminates the objectionable features of the prior art systems and renders the starting system positive in operation under all conditions.

One object of the present invention is to provide a starting system in which reclosing of the starting motor switch is controlled by a time delay mechanism mechanically responsive to the rotation of a shaft or the like which is rotated in accordance with the operation of the vehicle engine. In this manner the starting motor cir-

cuit can never be reclosed, in case of a false start or stalling of the engine, until a predetermined time after the engine has come substantially to rest. This time delay is not dependent upon a minimum generator current, a vibrating reed or the like, but is a direct function of the operation of the engine, and cannot produce closing of the starting switch until after the engine has ceased to rotate.

Another object of the present invention is the provision of a time delay mechanism which is entirely independent of generator current, so that it is operative regardless of the functioning of the generator to produce current. Thus, the starting system is provided with a mechanically responsive time delay mechanism controlled solely by the rotation of a suitable member driven as a result of the operation of the engine. This member may comprise the engine crankshaft, the cam shaft, the distributor shaft, the generator shaft, or the like.

A further advantage secured by the present invention is the provision of a time delay mechanism of simple and compact design, which can be readily mounted within a housing and secured directly to a generator housing or the like without requiring any extensive re-designing or re-organization of the existing motor structure and ignition system.

Another object of the present invention is to provide an automatic starting system in which only one relay is required in the control circuit for the starting switch, and the control of this circuit upon stopping of the engine is accomplished by a time-controlled snap switch, preventing the customary arcing at the contacts which has heretofore been an objectionable feature of such switches.

Still another feature of the present invention resides in the provision of a compensating mechanism included in the time delay mechanism to maintain the time delay substantially constant irrespective of temperature variations.

Other objects and advantages of the present invention will appear more fully from the following detailed description which, taken in conjunction with the accompanying drawing, will disclose to those skilled in the art the construction and operation of a preferred form of the present invention.

In the drawing:

Figure 1 is a diagrammatic circuit illustrating the starting system of the present invention;

Figure 2 is a detailed view of the time delay mechanism as it is initially actuated;

Figure 3 is a view showing a modified form of control mechanism;

Figure 4 is a diagrammatic perspective view of the time delay mechanism mounted on the generator of the vehicle; and

Figure 5 is a diagrammatic view of a modified starting circuit.

Referring now in detail to Figures 1 and 2 of the drawing, I disclose an internal combustion engine 5, provided with the usual type of transmission 6, and having a starter motor 7 connected thereto for cranking the engine 5.

The control circuit for actuating the starter motor 7 comprises a battery 8, connected through the conductor 9 to an ignition switch 10, the ignition switch being connected through conductor 12 to an energizing coil 13 for controlling operation of the starting motor switch 14, the current being divided from the coil 13 through the conductors 15-16 to respective pairs of contacts 17 and 18, the pairs of contacts 17 and 18 being connected through the armatures 19 and 20, respectively, with ground at 22 and 23, respectively.

A suitable core 24 is provided for controlling the operation of the armature 19, the armature 19 being mounted upon a pivot 25 disposed intermediate its ends, and being normally biased in a counter-clockwise direction by means of the spring 26, thereby normally tending to maintain the contacts 17 open.

The armature 20 is controlled by core 27, the armature 20 being pivoted at 28 and being normally biased to contact-closed position by means of the spring 29 at the opposite end thereof.

35 A control circuit for the contacts 18 is provided which comprises the ignition switch 10 connected through conductors 12 and 30 to a coil 32 for energizing the core 27, the coil 32 being connected through the conductor 33 to a contact 34 forming a part of the time delay control mechanism. The core 24 is energized by a single turn 35 of the conductor 9 leading through the conductor 36 to one contact 37 of the starting motor switch 14. The other contact 38 of this switch 45 is connected through the conductor 39 to the starting motor terminal 40, the starting motor being grounded as indicated at 41.

Referring now in more detail to the time delay mechanism, the contact 34 is adapted to be engaged by the resilient contact fingers 42 carried by the control member 43 which is pivoted at its lower end 44 for rotative movement to bring the contact fingers 42 into and out of engagement with the contact 34. The control member 43 is 55 connected to ground as indicated at 45.

The operation of the time delay mechanism is controlled by a shaft 46, which shaft is rotated during operation of the engine 5, and may comprise either the generator shaft, the cam shaft, 60 the crank shaft, or the distributor shaft of the engine, being any shaft which is responsive to self-operation or spinning of the engine 5 and rotates only when the engine 5 is being cranked or is operating.

65 The shaft 46 is provided with an eccentrically mounted cam member 47 which, during operation of the engine 5, rotates in the direction indicated by the arrow. The control member 43 is provided with an arcuate portion 48 which is adapted to extend about the cam member 47, and which is engaged by the cam surface of the member 47, when in the position shown in Figure 2, whereby it is moved in a clockwise direction about its pivot 44, bringing the contact fingers 75 42 into engagement with the contact block 34.

Connected to the arcuate portion 48 of the control member 43 is an arm or rod member 49 which extends into a suitable cylinder 50. The rod at its inner end has a piston member 52 adapted to be reciprocated within the cylinder 50 upon rocking movement of the member 43 about the pivot 44.

The piston 52 is provided with a by-pass or metered opening 53, and the cylinder 50 is filled with oil of suitable viscosity whereby the mechanism forms a dash pot for delaying the movement of the control member 43 by reason of the displacement of the oil from one side of the piston 52 to the other side thereof through the opening 53.

15 The control member 43 is normally biased in a counter-clockwise direction about its pivot 44 by means of the tension spring 54, connected to the control member 43 above its pivot 44, and at its opposite end connected to the extending end 20 55 of a thermostat member 56 mounted on a fixed support 57. The thermostat member 56 is preferably formed as a bimetallic strip of metal, the two metallic strips having different coefficients of expansion. Upon increase in temperature, the member 56 is adapted to spread outwardly, the end 55 moving to the right and decreasing the tension in the spring 54. Upon decrease in temperature, the member 56 contracts, moving the end 55 inwardly or to the left as 30 viewed in Figure 1, and thereby producing an increased tension in the spring 54.

25 In the operation of the starting system shown in Figure 1, the various parts of the device, when the engine is not in operation, are as 35 shown in Figure 1, with the major portion of the cam member 47 disposed to the left of the shaft 46.

In order to start the engine 5, the ignition switch 10 is closed. This completes a circuit 40 from the battery 8 through the conductor 9 and conductor 12 to the coil 13, and from the coil 13 through the conductor 16, the closed contacts 18, which are normally held closed by the spring 29, the armature 20 and the fulcrum 28 to ground at 23. Closing of this circuit at the ignition switch therefore results in energization of the coil 13, resulting in closing of the switch 14 across the contacts 37 and 38, and therefore resulting in flow of current from the battery through the conductors 9, 36 and 39 to the starter motor, thus producing cranking of the engine 5. During the initial actuation of the starting motor 7, a heavy flow of current is required, due to the cranking effort applied, and consequently a heavy current 50 flows through the single turn 35 of the conductor 9 about the relay 24. This energizes the core 24 to rotate the armature 19 about its pivot 25 to close the contacts 17. Closure of these contacts results in a circuit being completed through the 60 switch 10, conductor 12, conductor 15, contacts 17 and pivot 25 to ground at 22, thereby providing a second path for current flow through the coil 13. As long as the cranking effort is being applied by the starting motor 7, heavy current 65 is required, and consequently the contacts 17 are maintained closed to maintain the coil 13 energized.

Upon initial rotation of the engine 5 under the cranking effort imparted thereto by the starting 70 motor 7, the shaft 46, which rotates in response to rotation of the engine 5, rotates to bring the major portion of the cam 47 against the inner surface of the arcuate portion 48 of the control member 43, moving this member to the right, as 75

shown in Figure 2, and thus resulting in engagement of the contact fingers 42 with the contact block 34. At the same time the piston 52 is moved inwardly of the cylinder 50, displacing oil through the opening 53 to the rear side of the advancing piston.

The initial rotation of the cam 47 therefore results in closing of the circuit from the ignition switch 10 through the conductor 30, coil 32 and conductor 33 to ground at 45. This results in energization of the core 27, attracting the armature 20 downwardly about its pivot 28, and thereby breaking the circuit at the contacts 18. Thus the circuit through the coil 13 is maintained 15 through the closed contacts 17 which are held closed by the heavy flow of current to the starting motor.

Upon initial self-operation of the engine, the flow of current to the starting motor 7 is considerably reduced, and the core 24 is therefore de-energized, whereupon the spring 26 rotates the armature 19 about its pivot 25 to open the contacts 17, deenergizing the coil 13, since the contacts 18 have already been opened upon initial 25 operation of the engine 5. This results in opening of the switch 14, breaking the circuit extending to the starting motor 7, and thus deenergizing the starting motor.

As long as the engine 5 is maintained in self 30 operation, therefore, the armatures 20 and 19 are held away from their contacting engagement and maintain the starting switch 14 deenergized.

Due to the continuous rotation of the shaft 46 during self operation of the engine, the control member 43 is maintained in locked position so that the contacts 42 and 34 maintain a closed circuit to ground at 45. The cylinder 50 and piston 52 also provide a dash pot action which delays the movement of the control member 48 outwardly under the influence of spring 54, and the coil 32 is therefore maintained energized to hold the contacts 18 open. However, if the engine makes a false start, that is, fires for one or two cycles of operation and then stalls, it is desirable to 40 close the switch 14 in order to re-actuate the starting motor. It is necessary, however, to provide some means for preventing closure of the switch 14 before the engine 6 comes to rest, otherwise there will be a clashing of the starting gears, and no cranking effort will be applied to the engine. For this purpose the time delay mechanism is 45 provided, whereby upon the cessation of rotation of the shaft 46, the major portion of the cam 47 will move to a position outwardly to the left of the center of shaft 46, as is well known. The control member 43 will still be maintained in its inward position with the contacts 42 and 34 in engagement, however, due to the restricted flow of oil through the passageway 53. A predetermined time delay is thus provided, by controlling the size of the opening 53, to assure that after the shaft 46 comes substantially to rest there will still be a fixed time interval before the control member 43 will move outwardly under the tension of spring 54 to open the engagement between contacts 34 and 42.

Upon opening of the circuit between the contacts 42 and 34, the coil 32 is deenergized, and the armature 20 moves into contact-closed position under the influence of spring 29. This provides a closed circuit for the coil 13, thereby energizing this coil and closing the switch 14 to reenergize the starting motor 7. It is obvious, therefore, that the starting motor 7 will not be reenergized until after the engine has come to a complete 75

stop, due to the time delay provided by the dash pot connected to the control member 43.

Similarly, if the engine, after it has been in operation for a considerable length of time, stalls for some reason, the same operation will be repeated, namely, a fixed time delay will be effected after the shaft 46 comes to a complete stop, before the contacts 42 and 34 will be opened to close the circuit through the coil 13 to reclose the 5 starter motor switch 14.

In order to compensate for variations in the viscosity of the oil within the cylinder 50, I provide the thermostat 56 which increases the tension on the spring 54 upon decreases in temperature, whereby the resistance to flow of the oil 15 is automatically compensated for by the increased tension of the spring so that the time delay remains substantially constant. Similarly, upon increases in temperature which would decrease the viscosity of the oil within the cylinder 50, the 20 thermostat 56 operates to decrease the tension in the spring 54, so that at all times the time delay effected by the dash pot mechanism is maintained substantially constant, and therefore the operation of the time control mechanism for controlling the opening and closing of contacts 42 and 34 25 will be maintained substantially constant.

In Figure 3 I have shown a modified embodiment of the invention in which a rotatable shaft 60 is provided which is controlled by operation of 30 the engine 5, and is provided with a cylindrical member 62 mounted coaxially thereto, the member 62 being engaged by the curved portion 63 of a control member 64 carrying a contact 65 at its free end. At the opposite end, the control member 64 is connected to a spring 66 tensioned between the end of the control member and a fixed 35 grounded support 67.

The contact 65 of the control member 64 is adapted to engage a corresponding contact 68 40 connected through a conductor 33' to a coil such as the coil 32 of Figure 1. In the operation of the control mechanism shown in Figure 3, rotation of shaft 60 in the direction indicated by the arrow results in movement of the control member 64 in a counter-clockwise direction about the shaft, due to the frictional engagement between the curved portion 63 thereof and the surface of the member 62. This results in closing of contact between the contacts 65 and 68, completing 45 a circuit through the coil, such as the coil 32, for opening the grounded path through the energizing coil 13 of the starter switch 14. This opening of the circuit through the coil 13 results in maintaining the starter motor switch 14 in 50 open position as long as the shaft 60 is rotating. Upon stopping of the shaft 60, the spring 66 draws the control member 64 in a clockwise direction about the member 62, moving the contact 65 away from the contact 68, and thereby 55 opening the circuit through the coil 32, whereby the grounded path through the actuating coil 13 of the starter motor switch 14 is closed to reclose the starter motor switch. Inasmuch as the frictional engagement between the portion 63 of the 60 member 64 and the surface of the member 62 is such that the spring 66 will not snap the control member 64 away from contact engagement until the shaft 60 has come to a complete rest, it is 65 obvious that the starter motor switch will not be closed until the engine 5 has come to a complete rest, which is the desired condition which should be attained before the starter motor is re-actuated.

The structure shown in Figure 4 shows the 75

application of the present control mechanism to the generator shaft of a motor vehicle. In this figure I have diagrammatically indicated a generator 10, mounted upon a suitable support 12, 5 and carrying at its rear end a housing 13 in which is disposed the time delay control mechanism shown in Figure 1, corresponding reference numerals indicating corresponding parts of the time delay mechanism. It is thus apparent that 10 I may mount the entire time delay control mechanism upon the end of the generator housing, whereby the automatic starting circuit of the present invention may be directly incorporated upon present type motor vehicles without requiring 15 any extensive changing or reorganization of the structure. By mounting the entire control mechanism within this housing, it may be readily applied to a generator or any other rotating part of the engine, and provides a compact and simplified starting circuit control mechanism.

Obviously, the control mechanism contained within the housing 13 could be equally well applied to the cam shaft, distributor shaft or crank shaft of the engine, with slight modifications. 25 The modified circuit shown in Figure 5 is similar in general to the circuit shown in Figure 1, but eliminates the core 27, coil 32, the armature 20 and contacts 18, the conductor 16 leading from the coil 13 being directly connected to a 30 normally closed snap switch 75 grounded at 76. This snap switch is provided with an extended operating handle 77 received in the forked end 78 of a control member 79 corresponding to the control member 43 of Figure 1. The remainder 35 of the circuit corresponds to that shown in Figure 1 and is indicated by corresponding reference numerals.

In the operation of the circuit shown in Figure 5, the initial cranking of the engine by the starting motor 7 results in rotation of cam 47, moving control member 79 to the right, and snapping the operating lever 77 of switch 75 to the right, opening the circuit between the contacts of the switch to provide for deenergization of coil 13 40 upon reduction in current flow through turn 35, which causes opening of contacts 17. As long as the engine is self-operating or spinning, the control member 79 is held to the right, keeping switch 75 open. Upon substantial stopping of 45 the shaft carrying cam 47, the spring 54 urges the member 79 to the left, being restrained by the dash pot 58 until the oil is displaced through the piston. However, this time delay provides for assuring that the engine will come to a complete 50 rest before the end 78 of member 79 moves lever 77 over center position to snap the switch closed.

This snap action switch prevents any arcing at the contacts during the slow return movement of the member 79 to the left. It is obvious that 55 such a switch construction could be readily incorporated in place of contacts 34 and 42 in Figure 1, and the invention is to be understood as embracing such a construction.

The essential feature underlying the present 60 invention is the provision of a time delay control mechanism which is mechanically responsive to rotation of an engine-driven part, and provides for control of a suitable circuit to prevent closure of the starting motor switch until after such time 65 as the engine comes to a complete rest. The provision of the constant time delay dash pot provides for a constant time delay to insure that all parts of the engine have completely stopped before the circuit for reenergizing the starter motor switch is completed.

It will be apparent that no reliance upon current produced by the generator driven by the engine, or from any other similar electrically controlled circuit, is necessary. In this connection the entire arrangement comprises a mechanical control of the time delay mechanism in response to engine operation. Further, the time delay is coordinated directly with the rotative effort produced by the engine, so that no re-closure of the circuit can be made even if the 10 engine spins for a relatively long period of time, since the circuit for reenergizing the starter motor switch will not be closed until after the engine comes to a complete rest. It is believed that these features are broadly new over the constructions with which I am familiar.

Having described my invention in accordance with the patent statutes, what I claim as new and desire to secure by Letters Patent is:

1. In a starting system for internal combustion engines, a control circuit for said system including a normally closed set of contacts, means including mechanical means operated in response to operation of said engine for holding said contacts apart, means for introducing 20 a time delay in reclosure of said contacts after said engine has stopped operating, and means for maintaining said time delay constant during temperature variations.

2. In an electric system for internal combustion engines, a starting system including a magnetic starting switch, a control circuit therefor including two sets of contacts in parallel, one set of said contacts being normally open and the other set being normally closed, means responsive to cranking of said engine for closing said normally open set of contacts, means responsive to operation of said engine for opening said normally closed set of contacts, means responsive to self-operation of said engine for opening 40 said normally open contacts, and means for maintaining a substantially constant time delay in closing of said normally closed contacts after said engine comes to rest, independent of temperature variations.

3. In a starting system for internal combustion engines, a magnetic starting switch, a control circuit therefor, a shaft rotated upon cranking of said engine, means controlled by operation of said shaft for opening said control circuit during operation of said engine, said means providing for closing of said circuit when said shaft stops rotating, means for introducing a predetermined time interval between stopping of rotation of said shaft and closing of said circuit, and compensating means for maintaining said time interval constant during variations in surrounding temperature.

4. In combination, an internal combustion engine, a shaft driven thereby, a cam mounted on 60 said shaft, a starting system for said engine including a control circuit therefor, a pair of normally closed contacts in said control circuit, magnetic means for opening said contacts, a secondary circuit for energizing said magnetic 65 means, means operated by said cam for closing said secondary circuit upon rotation of said shaft, fluid-controlled means for holding said circuit closing means in closed position during rotation of said cam, and spring means tending to open 70 said secondary circuit and operable to open the same when said shaft comes substantially to rest, said fluid controlled means delaying the action of said spring means for a predetermined time after said shaft comes substantially to rest.

5. In combination with an internal combustion engine, means for cranking said engine, control means therefor having two sets of contacts in parallel, one set of said contacts being held closed only during cranking of said engine, the other set of contacts being normally closed, means including cam means for opening said normally closed contacts upon initial cranking of said engine and maintaining said contacts open during any movement of said engine, and means for closing said contacts a predetermined time after said engine comes to rest.

10 6. In an automatic starter control for internal combustion engines, a magnetic starting switch and a control circuit therefor including a pair of normally closed contacts, means for opening said contacts including an element movable by rotation of the engine to be started, yielding means for returning said element to normal position, and thermostatic means for varying the tension of said yielding means.

15 7. In an automatic starter control for internal combustion engines, a magnetic starting switch and a control circuit therefor including a pair

of normally closed contacts, means for opening said contacts including an element movable by rotation of the engine to be started, yielding means for returning said element to normal position, means for frictionally retarding such return movement, and thermostatic means for increasing the tension of said yielding means in response to decrease in temperature.

20 8. In an automatic starter control for internal combustion engines, a magnetic starting switch, a control circuit therefor including a set of normally closed contacts, means for opening said contacts including a switch element, an actuating element rotatable with a member of the engine to be started, a mechanical connection between said element and said switch element whereby movement of the actuating element in either direction of rotation intermittently moves the switch element positively to open said contacts, means for delaying motion of the switch element to close the contacts, and means for preventing interruption of the cranking operation until the engine becomes self-operative.

MARION W. MORRIS.
